UNITED STATES PATENT OFFICE.

RALEIGH H. STALEY, OF SPRINGFIELD, ILLINOIS, ASSIGNOR TO THE BAKER MANUFACTURING COMPANY, OF SPRINGFIELD, ILLINOIS, A CORPORATION OF ILLINOIS.

SCRAPER ELEVATING AND LOWERING MECHANISM.

Application filed December 3, 1924. Serial No. 753,718.

To all whom it may concern:

Be it known that I, RALEIGH H. STALEY, a citizen of the United States, residing at Springfield, in the county of Sangamon and State of Illinois, have invented certain new and useful Improvements in Scraper Elevating and Lowering Mechanism, of which the following is a specification, reference being had therein to the accompanying drawing.

My invention relates to new and useful improvements in a device or mechanism for raising and lowering the scraper blade of graders, scrapers, snow plows, bulldozers, back fillers, or the like, and more particularly to such a device or mechanism which is automatically operated by the movement of the machine, of the above character, to which it is attached.

The principal object of the invention is the provision of elevating and lowering mechanism of such a character that as the machine moves forward in its scraping direction that the scraper blade will be lowered but when the machine is moved rearwardly the scraper blade will be raised.

A further object of the invention resides in the provision of means whereby the elevating and lowering mechanism may be locked or held in either of its positions or in other words in a position to hold the scraper blade elevated or in a position to hold the scraper blade lowered.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me it will be understood that such changes may be made as will fall within the scope of the appended claims.

In the drawings:

Fig. 1 is a side elevation with parts in section showing the blade in lowered position.

Fig. 2 is a side elevation showing the scraper blade in raised position.

Fig. 3 is a top plan with parts broken away.

Fig. 4 is a front view with parts shown in section and parts shown diagrammatically.

Fig. 5 is a detailed perspective of one of the runners and its associate plates and rollers, the runner having parts shown in transverse section.

Fig. 6 is a side elevation illustrating a slightly modified form of elevating and lowering device.

In the drawings A denotes generally a machine such as a grader, scraper, snow plow, bulldozer, back filler, or the like, which is conveyed from place to place by the tractor belts B, the belts being driven in the usual manner and as the machine itself and the tractor belts form no particular part of the present invention a further detailed description is not thought necessary. Connected to the machine, preferably adjacent the rear end thereof, is a tractor draw bar 1 to which is secured by means of the plates 2 a frame which extends entirely around the machine, said frame comprising, the side beams 3 the rear end beam 4, and the front beam 5 to which the scraper blade 6 is secured. The plates 2 are connected to the draw bar 1 by means of the bolts 7 or other suitable fastening means and to the rear end beam 4 of the frame by means of the bolts or other securing devices 8. It will thus be seen that the rear end of the frame is connected to the machine whereas the forward end is adapted for vertical movement being normally held in its lowered position, with the blade 6 in contact with the ground or other surface by gravity.

Secured to the top of each of the side beams 3 of the frame, preferably adjacent the forward ends thereof, are the vertically extending standards 9 and 10 the standard 10 being of a somewhat greater height than the standard 9 for a purpose which will readily appear. The standards are secured to the top of the beams 3 by means of the bolts 11 or other suitable securing devices

and secured between the standards 9 and 10 by the angle iron plates 12 are the inclined tracks 13 and 14, of T-iron construction, and vertically spaced as quite clearly shown, the lower ends of the tracks being secured to the standard 9 and the higher ends to the standard 10.

Runners are shown at 15 and are adapted to contact with the ground or other surface

- 19 at all times, each of said runners 15 having vertically extending plates 16 secured thereto, said plates extending on opposite sides of the side beams 3, as quite clearly illustrated in the drawings, and being of a
- 15 height as to preferably reach to a point adjacent the top of the upper track 13. Rotatably mounted or connected between the plates 16, adjacent the upper edges thereof are the longitudinally spaced rollers 17
- 20 which engage between the tracks 13 and 14, the rollers having flanges 17' formed on their ends and the forward roller being on a somewhat lower level than the rear roller. When the scraper blade is in lowered position the rear roller will engage the standard 10 and when the scraper blade is in its raised position the forward roller will engage the standard 9. The runners 15 have the upwardly extending flanges 15' provided with
- 25 the shoulders 16' upon which the lower edges of the plates 16 are received. Secured to the outer face of each of the outer plates 16 is a bearing or guide plate 18 to which one end of a lever 19 is pivotally connected
- 30 at 20. The lever is formed at its upper end with the hand-hold 21 and is provided in its lower edge with the notches 22 and 23, said notches 22 and 23 receiving, when desired, the transversely extending pin 24 supported in the U-shaped bearing 25 which in turn is secured to the top of the beams 3 by means of the bolts 26 or other suitable fastenings. Each of the outer plates 16 has an opening 27 formed therein, said opening
- 45 receiving a pin 28 which engages the notched edge of the lever 19 to hold the lever in elevated position, as more clearly illustrated in Figs. 1 and 2 of the drawings, with the notches 22 and 23 disengaged from the transversely extending pin 24.

In Fig. 6 of the drawings I have shown a slightly modified form of device for raising or lowering the frame. In this form of the invention instead of having the runners 15 for engagement with the ground I provide the rollers or wheels 29 which are rotatably mounted between the plates 16 adjacent their lower edges and extend below the lower edge thereof, and engage the ground or other surface over which the machine is passing. Secured to each of the wheels or rollers 29 is a ratchet wheel 30 and engaging each of the ratchet wheels is a pawl 31 to which rods or levers 32 are connected. The

teeth of the ratchet wheels 30 extend in such a direction that the wheels are adapted to rotate as the machine is moved forward but when the machine is moved rearwardly the pawls 31 hold the wheels against rotation thereby causing friction upon the ground or other surface to hold the plates 16 stationary until the machine is moved in such a position that the front rollers 17 carried by the plates engage the standard 9.

Having fully described the detailed construction of both the preferred and modified forms of my invention I will now endeavor to somewhat more clearly bring out the operation. It is a well known fact that in the use of machines of various characters employing scraper blades that it is often necessary for the machine to be moved rearwardly, or "backed up" to make a fresh start or to be moved to a different location and when this is done it is preferable to be able to raise the scraper blade so that the dirt or other material will not be drawn rearwardly by the machine and when the machine is again moved forwardly it is desired that the scraper blade be lowered. It can readily be appreciated that advantages are secured by having this raising and lowering mechanism automatically operated so that the operator of the machine may give his full attention to manipulation of the machine and does not have the additional burden of operating the raising and lowering mechanism. In Fig. 1 of the drawings I have illustrated the raising and lowering mechanism in position when the machine is being moved forwardly or in its scraping operation with the blade in contact with the ground. As has been stated the runners 15 will always contact with the ground or other surface and with the scraper blade lowered the rollers 17 carried by the plates 16, will be engaged with the highest points of the track 13 and 14 and the rear rollers in engagement with the standards 10. The engagement of the rollers with the standards 10 cause the runners and plates to be moved forwardly with the machine it being understood that the traction of the machine is such that the frictional contact with the ground or other surface is overcome. When the machine is moved rearwardly the friction of the runners with the ground or other object is sufficient to hold the plates 16 with their associated rollers stationary and the movement of the machine will cause the inclined tracks 13 and 14 to be moved over the rollers, such movement raising the forward end of the frame and the scraper blade 6 upwardly, this being accomplished by the fact that the forward ends of the tracks 13 and 14 are on a lower level or plane than the rearward ends thereof. As the front rollers contact with the standards 9 the frictional engagement of the runners 15 with the ground will be overcome and the runners

and their associated mechanism carried rearwardly with the machine holding the scraper blade and the forward end of the frame in raising position as more clearly illustrated in Fig. 2 of the drawings. When the machine is again moved forwardly the frictional contact of the runners with the ground or other object will hold the plates 16 and the rollers 17 and will allow the inclined tracks 13 and 14 to pass thereover in a forward direction the forward end of the frame and the scraper blade being lowered during such movement until the rear rollers 17 contact with the standards 10 when the runners 15 and their associated mechanisms will move forwardly with the machine. The levers 19 are normally held in the raised position shown in Figs. 1 and 2 by the pins 28 to allow the movements of the raising and lowering mechanism as above described. At times it might be desired to hold the raising and lowering mechanism in either of its positions and when this is desired the pins 28 may be removed so that the levers 19 may be lowered with their lower edges received in between the side of the U-shaped bearing 25 so that either the notch 22 or the notch 23 will engage the transversely extending pins 24. When it is desired to hold the scraper blade raised the pins 28 will be received in the notches 23 of the levers 19 and when it is desired to hold the raising and lowering mechanism with the scraper blade lowered the notches 22 of the levers 19 will receive the transversely extending pins 24.

The operation of the modified form of the invention as shown in Fig. 6 is substantially the same as that above described except that I use the wheels or rollers 29 instead of the runners 15. The wheels or rollers 29 will freely rotate as the machine is moved forwardly but as the machine is moved rearwardly the pawls 31 will hold them against rotation, thereby causing such frictional engagement with the ground or other object as to hold the plates 16 and rollers 17 stationary so as the tracks 13 and 14 will pass thereover and raise and lower the frame and scraper blade as has been previously described. The pawls 31 may be disengaged from the ratchet wheels 30 by means of the rods or levers 32.

Having fully described my invention what I claim as new and desire to secure by Letters Patent is:

1. The combination with a machine of the character described including a movable frame and a scraping blade connected thereto, of a track carried by the frame, and means engageable with the track and operable by the movement of the machine for raising and lowering the blade.

2. The combination with a machine of the character described including a movable

frame and a scraping blade connected thereto, of an inclined track carried by the frame, and means engageable with the track and operable by the movement of the machine for raising and lowering the blade. 70

3. The combination with a machine of the character described having a movable frame and a scraper blade connected thereto, of a track carried by the frame, and a member engageable with the surface over which the machine is passed and engageable with the track for raising and lowering the scraper blade upon movement of the machine. 75

4. The combination with a machine of the character described having a movable frame and a scraper blade carried by the frame, of a track carried by the frame, and means engageable with the track for raising the scraper blade upon movement of the machine in one direction and lower the scraper blade upon movement of the machine in the opposite direction. 80

5. The combination with a machine of the character described having a movable frame and a blade connected thereto, of an inclined track carried by the frame, and means engageable with the surface over which the machine is passed and engageable with the inclined track whereby the frame and its associated scraper blade will be raised as the machine is moved in one direction and lowered when the machine is movable in the opposite direction. 85

6. The combination with a machine of the character described having a movable frame and a scraper blade carried thereby, of a track carried by the frame, a plate, a roller carried by the plate and engageable with the track, and a member carried by the plate and engageable with the surface over which the machine is operated, the plate being movable relative to the frame upon movement of the machine for raising and lowering the blade. 90

7. The combination with a machine of the character described including a movable frame and a scraping blade connected thereto, of means engageable with the ground and movable longitudinally of the frame for raising and lowering the blade. 105

8. The combination with a machine of the character described including a vertically movable frame and a scraping blade connected thereto, of means engageable with the ground and movable longitudinally of the frame for raising and lowering the blade. 110

9. The combination with a machine of the character described including a movable frame and a scraping blade connected thereto, of means engageable with the ground and movable longitudinally of the frame for raising and lowering the blade, and means engageable between the frame and movable 120

125

130

member for holding the movable member in position with the blade raised.

10. The combination with a machine of the character described including a movable frame and a scraping blade connected thereto, of means engageable with the ground and movable longitudinally of the frame for raising and lowering the blade, and

means carried by the movable member and engageable with the frame for holding said movable member in position with the frame raised. ¹⁰

In testimony whereof I hereunto affix my signature.

RALEIGH H. STALEY.
